ELECTRIC SWITCH

Jakob Kopeliovitch and Willi Wanger, Baden, Switzerland, assignors to Aktiengesellschaft Brown Boveri & Cie., Baden, Switzerland, a joint-stock company of Switzerland

Application November 11, 1933, Serial No. 697,580
In Germany November 11, 1932

7 Claims. (Cl. 200—150)

This invention relates in general to electric switches having pressure vessels and more particularly to switches in which a limited amount of arc extinguishing fluid contained in a pressure vessel is used for extinguishing the arc exteriorly thereto.

In switches employing a reduced amount of arc extinguishing fluid, the arc produced upon disengagement of the contacts is generally extinguished by deionization due to the contact and proximity of the arc with vapor produced from the fluid. If such vapor is produced by drawing the arc out within a body of fluid, a large amount of fluid becomes necessary. In addition, when the switch is being closed the moving contact must then travel through an appreciable depth of fluid previous to engaging with the fixed contact, thereby establishing a protracted connection of the circuit through the fluid during the closing operation. If the arc extinguishing fluid utilized is appreciably conductive, as is the case when undistilled water is utilized, sufficient current may flow between the contacts during closing operation to cause large amounts of vapor to be produced, thereby hindering or even preventing completion of the closing operation. The fluid to be vaporized may also be forced into the arc path; if the clearance between the moving contact and the fluid constituting a passage therefor is small, difficulty is then experienced in displacing a sufficient amount of fluid and, if such clearance is large, the fluid is inefficiently utilized. In either of the above cases the interrupting operation becomes uncertain and variable.

By providing, outside of the pressure chamber, a passageway closely confining the movable contact and the arc, and by providing a flow of fluid through other passageways to chambers communicating with the passageway in which the arcing takes place, an efficient flow of fluid is easily produced and the interrupting operation is rendered rapid and certain.

It is therefore among the objects of the present invention to provide an electric switch of the pressure chamber type in which the moving contact and the arc terminating thereat are closely confined within an arcing passageway.

Another object of the present invention is to provide an electric switch of the pressure chamber type in which the passageway confining the arc is in communication with chambers receiving arc extinguishing fluid only during interrupting operation of the switch.

Another object of the present invention is to

provide an electric switch of the pressure chamber type in which the arc extinguishing fluid is vaporized by the arc at a plurality of points in the arc path.

Another object of the present invention is to provide an electric switch of the pressure chamber type in which a flow of arc extinguishing fluid is produced under pressure resulting from striking of the arc.

Another object of the present invention is to provide an electric switch of the pressure chamber type in which the flow of arc extinguishing fluid is obtained partly by movement of pump means controlled by the movable contact.

Objects and advantages other than those above described will be apparent from the following description when read in connection with the accompanying drawing, in which:

Fig. 1 is a vertical cross-sectional view of one embodiment of the present invention in which the arc extinguishing fluid is displaced under a pressure generated by vaporization of a portion of such fluid in the arc; and

Fig. 2 is a vertical cross-sectional view of another embodiment of the present invention in which displacement of the arc extinguishing fluid is obtained partly by means of a piston moving in the pressure chamber of the switch.

Referring more particularly to the drawing by characters of reference, reference numeral 6 designates a vessel forming a pressure chamber 7 for an electric switch and containing a body of arc extinguishing fluid 8. Vessel 7 contains the fixed contact structure 9 of the switch, which may be of any suitable kind known in the art and which is provided with suitable conductive connections (not shown) for the purpose of completing the electric circuit of the switch. Contact 9 is immersed in the fluid preferably in close proximity to the surface thereof. A movable contact 11, preferably of a rod shape, closes the circuit of the breaker by engaging with contact 9 and may be guided and operated by any well known mechanism (not shown). When the switch is in the closed position and contact 11 engages with contact 9, contact 11 is surrounded over a substantial portion of the length thereof by a member 12, preferably constituted of insulating material, and provided with a passageway 13 closely confining contact 11 without however hindering movement thereof. Member 12 is supported in fixed relation with respect to vessel 6 in any suitable manner, as for instance by cementing member 12 into a flange 14 constituting a cover for vessel 6.

Member 12 is provided with one or more chambers 16 which are in communication with passageway 13. Some or all of chambers 16 are connected with chamber 7 by means of passageways 17 likewise provided in member 12. Such connection may be effected in any desired manner; for instance, as illustrated in Fig. 1, some of chambers 16 may be provided with individual passageways whereas others may communicate 10 with a common passageway and others may be entirely without communication with the chamber 7. Member 12 is also preferably provided with an extension forming a circular partial partition 18 immersed in fluid 8, whereby passages 15 13 and 17 are sealed against direct connection therebetween through chamber 7. Member 12 may be formed from a single piece of material shaped to provide passageways 13 and 17, chambers 16 and is formed with partition 18. As illustrated 20 in Fig. 1, member 12 may also be constituted of a body 19 having a recess receiving a plurality of inserts such as 21 which define passageway 13 and chambers 16. Passageways 17 may then be provided between body 19 and the 25 several inserts contained therein. Partition 18 may be integral with the lowest insert. The inserts may be fastened within body 19 by any suitable means such as by means of a split collar 22 provided with apertures aligned with passageways 30 17. When it is desired to provide sufficient fluid for a number of successive operations of the switch and at the same time insure that the fluid level within the chamber remain substantially constant even with a reduced amount of fluid 35 within the pressure chamber, such chamber is provided with a reservoir 23 communicating therewith. Such communication is preferably effected through a relief valve 24 permitting flow of fluid from chamber 7 into reservoir 23 when 40 the pressure within the chamber is excessive, such valve being provided with a vent 26 permitting the slow flow of fluid therethrough to equalize the fluid levels in chamber 7 and in reservoir 23. Reservoir 23 may be closed by means 45 of a cover 27 to avoid evaporation of the fluid and introduction thereof of foreign matter; such cover may be provided with a filler opening closed by a vented plug 28.

To cause interrupting operation of the switch, contact 11 is moved upwardly out of engagement with contact 9 and is withdrawn from vessel 6 and from passageway 13. Upon disengagement of the contacts, an arc is established therebetween causing an intense vaporization of fluid 50 in the space enclosed within partial partition 18. Such space is therefore filled with vapor under considerable pressure and, as a result of the small clearance between contact 11 and passageway 13, the pressure developed by the arc causes 55 downward displacement of the fluid within partition 18 and upward displacement of the fluid in the remainder of chamber 7. The fluid rapidly reaches passageways 17 and is forced to flow therethrough and to fill chambers 16. Continued movement of contact 11 causes the arc between the contacts to be gradually extended over 60 part or all of the length of passageway 13. During such motion, contact 11 successively passes through the different chambers 16 and the fluid 65 then present in such chambers flows, by gravity, into the arc path at a plurality of points thereof where such fluid is vaporized by the heat of the arc. The arc is thereby deionized and caused to be extinguished, and the excess fluid present in 70 chambers 16 at the end of the interrupting operation

is returned into chamber 7 by gravity. During such operation, fluid is forced from chamber 7 into reservoir 23 through vent 26, but such flow is practically inappreciable as a result of the small dimensions of vent 26. If, however, 5 the pressure within vessel 6 reaches a value which might damage any of the portions of the switch, valve 24 opens and permits a substantial flow of fluid from chamber 7 into reservoir 23 thereby relieving the excess pressure within the chamber. 10

When the switch is being reclosed, contact 11 penetrates into passageway 13 and into chamber 7 and immerses in fluid 8 before engaging with contact 9. Contacts 9 and 11 are thus connected by fluid 8 during a length of time which is however inappreciable as a result of the location of contact 9, and any vapor produced by the flow of current between the contacts through the fluid 15 will be negligible in amount.

In the embodiment illustrated in Fig. 2, contact 9 is provided with a passageway extending therethrough and is supported within vessel 6 from the side walls thereof. The lower portion of vessel 6 constitutes a cylinder receiving a piston 29. Such piston is biased upward by means 25 of a spring 31 resting on a closure plate 32 separating chamber 7 from reservoir 23. Piston 29 is provided with a valve 33 permitting flow of fluid from the lower side to the upper side thereof within chamber 7, and closure plate 32 is likewise 30 provided with a valve 34 permitting flow of fluid from reservoir 23 into chamber 7. Such valves are therefore operable to permit the flow of fluid from reservoir 23 into chamber 7 upon reciprocating motion of piston 29, such motion being 35 effected by the combined actions of contact 11 and spring 31 on the piston. In the present embodiment, member 12 is constituted of a plurality of aligned annular members such as disks 36 defining the passageways 13 and 17 and the chambers 16. Members 36 are maintained in engagement with each other and with the upper portion of vessel 6 by means of a spring 37 maintained under pressure by suitable means. Such means preferably comprise a cover 38 mounted 40 on an insulating bushing 39 cemented into a flange 41, such assembly constituting a cover for reservoir 23. Reservoir 23 may be provided with a level gauge 42 having a filler cap 43 and need not be vented due to the clearance between contact 11 and cover 38. 45

When contact 11 is withdrawn to cause interrupting operation of the switch, such contact initially slides through contact 9 while remaining in conductive engagement therewith. Spring 31 55 then causes piston 29 to move upward, thereby forcing flow of fluid through passageways 17 to chamber 16. Fluid is then also drawn from reservoir 23 through valve 34 into the lower part of chamber 7. Continued movement of contact 11 60 causes such contact to disengage from contact 9 whereby an arc is struck between the contacts 9 and contact 11. Such arc causes continued displacement of fluid 8 in the manner above described with respect to the embodiment illustrated 65 in Fig. 1, thereby cooperating with piston 29 in causing the transfer of fluid. During such operation, some of the vaporized fluid condenses within cover 38 and bushing 39 and is returned to reservoir 23, the unvaporized portion of the fluid 70 returning to chamber 7 by gravity. Piston 29 is then abutted against the supports of contact 9, thereby raising the fluid level within chamber 7 above that of reservoir 23. Fluid will then flow 75 from chamber 7 through vent 26 into reservoir 75

23 to bring the fluid therein at the same level. During the interrupting operation, excess pressures in chamber 7 are relieved by means of valve 24. Excess pressures within passageway 5 13 and chambers 16 may cause members 33 to momentarily disengage from each other against the action of the spring 37 to thereby allow vapor in chambers 16 to escape in the space within bushing 39 and thereby relieve the pressure within 10 chamber 16.

When the switch is being reclosed, contact 11 penetrates within passageway 13, engages with contact 9 and depresses piston 29 to the position shown, whereby the fluid present below the piston 15 is transferred to the space above such piston through valve 33 without changing the fluid level within chamber 7.

From the above description of the construction and operation of the present invention, it will be apparent that the displacement of arc extinguishing fluid from the pressure chamber into the arc path is obtained in an efficient and positive manner at a plurality of points of the arc, whereby the arc is extinguished rapidly and certainly. 20 Closure of the switch is likewise obtained in a positive and a certain manner even when the arc extinguishing fluid is conductive as a result of arranging substantially the entire arc path in air whereby the switch contacts remain perfectly insulated from each other during almost the entire 25 closing operation of the switch.

Although but a few embodiments of the present invention have been illustrated and described, it will be apparent to those skilled in the art that 30 various changes and modifications may be made therein without departing from the spirit of the invention or from the scope of the appended claims.

It is claimed and desired to secure by Letters 35 Patent:

1. In an electric switch, a vessel forming a pressure chamber, an arc extinguishing fluid contained within said chamber, a fixed contact within said pressure chamber immersed in said 40 fluid, a movable contact withdrawable from engagement with said fixed contact and from said pressure chamber, means arranged adjacent said vessel and defining a passageway closely confining said movable contact and defining a chamber in adjacent communication with said passageway, and means for causing said arc extinguishing fluid to fill the second said chamber only during interrupting operation of said switch, said means comprising a piston operable in response to movement of said movable contact and said means further comprising additional passageways providing communication between a point above said fluid in said pressure chamber and said second 45 said chamber.

2. In an electric switch, a vessel forming a pressure chamber, an arc extinguishing fluid retained within said chamber, a fixed contact within said pressure chamber immersed in said fluid and extending adjacent to the surface thereof, a movable contact withdrawable from engagement with said fixed contact and from said pressure chamber, means arranged adjacent said vessel defining a passageway closely confining said movable contact, a second chamber in adjacent communication with said passageway, and an additional passageway providing communication between said second chamber and a point above the surface of said fluid in said pressure chamber.

3. In an electric switch, a vessel forming a

pressure chamber, an arc extinguishing fluid retained within said chamber, a fixed contact within said pressure chamber in said fluid and extending adjacent to the surface thereof, a movable contact withdrawable from engagement with said fixed contact and from said pressure chamber, insulator means arranged adjacent said vessel and having a passageway closely confining said movable contact and having a chamber in communication with said passageway, and means for causing said arc extinguishing fluid to envelop said movable contact in the second said chamber only during interrupting operation of said switch, said means comprising a second passageway between said pressure chamber and said first mentioned passageway.

4. In an electric switch, a vessel forming a pressure chamber, an arc extinguishing fluid retained within said chamber, a fixed contact within said pressure chamber in said fluid and extending adjacent to the surface thereof, a movable contact withdrawable from engagement with said fixed contact and from said pressure chamber, means arranged adjacent said vessel and having a passageway closely confining said movable contact and having a plurality of closed chambers in communication with said passageway, and means for causing said arc extinguishing fluid to envelop said movable contact in at least some of said plurality of chambers only during interrupting operation of said switch, said means comprising a plurality of additional passageways providing communication between said some of said closed chambers and said pressure chamber.

5. In an electric switch, a vessel forming a pressure chamber, an arc extinguishing fluid retained within said chamber, a fixed contact immersed in said fluid within said pressure chamber and extending adjacent to the surface thereof, a movable contact withdrawable from engagement with said fixed contact and from said pressure chamber, a plurality of contiguous annular members arranged adjacent said vessel and aligned to form a passageway closely confining said movable contact and forming a plurality of closed chambers in adjacent communication with said passageway, means including additional passageways provided between certain of said closed chambers and said pressure chamber for causing said arc extinguishing fluid to envelop said movable contact in at least some of said plurality of chambers only during interrupting operation of said switch, and resilient means yieldably maintaining said annular members in contacting engagement when the pressure within said passageway remains below a predetermined value, said annular members momentarily disengaging when interrupting operation causes the pressure within said passageway to reach said predetermined value.

6. In an electric switch, a vessel forming a pressure chamber, an arc extinguishing fluid retained within said chamber, a fixed contact immersed in said fluid within said pressure chamber and extending adjacent to the surface thereof, a movable contact withdrawable from engagement with said fixed contact and from said pressure chamber, means arranged adjacent said vessel and having a passageway closely confining said movable contact and having a chamber in adjacent communication with said passageway, said chamber and passageway being connected with said pressure chamber at a point above

the level of said fluid, means for causing arc extinguishing fluid to be connected to the second said chamber upon occurrence of a pressure producing arc within the first said chamber, and 5 means responsive to movement of said movable contact and cooperating with the last said means to displace said arc extinguishing fluid.

7. In an electric switch, a cylindrical vessel forming a pressure chamber, a resiliently biased piston closing said chamber, a reservoir for arc extinguishing fluid, valve means operable to cause transfer of arc extinguishing fluid from said reservoir to said pressure chamber by reciprocating motion of said piston, a fixed contact within said pressure chamber, a movable contact extending

through said fixed contact against said piston and withdrawable from engagement with said fixed contact and with said piston and from said pressure chamber, and means arranged adjacent said vessel and having a passageway receiving said movable contact and constituting an arcing chamber therefor, said passageway being connected with said arcing chamber by passageways entering said pressure chamber at a point above the level of said fluid whereby said piston 10 causes flow of arc extinguishing fluid from said pressure chamber into said passageways only in response to withdrawal of said movable contact. 15
